(57) **CLAIM**

The ornamental design for a wide-brimmed hat, as shown and described.

DESCRIPTION

FIG. 1 is a front view of a design for a wide-brimmed hat. FIG. 2 is a left side view of the hat of FIG. 1, including a first rear side reflective crown panel represented by a repeating pattern of dots.

FIG. 3 is a right side view of the hat of FIG. 1, including a second rear side reflective crown panel.

FIG. 4 is a back view of the hat of FIG. 1, including the two rear side reflective crown panels.

FIG. 5 is a top view of the hat of FIG. 1, including the two rear side reflective crown panels; and,

FIG. 6 is a bottom view of the hat of FIG. 1.

The solid lines in FIGS. 1-6 illustrate a hat according to the present invention. The longer, evenly incremented dashed lines and the shorter, evenly incremented dashed lines are for the purpose of illustrating environmental structure and/or environmental stitching only and form no part of the claimed design. In FIG. 6, the combined dash-and-dot style line with lowest line weight represents a boundary line that encircles an interior portion of the hat crown, following the innermost encircling perimeter edge of the hat crown. The appearance of the interior portion of the hat crown encircled by the boundary line, as viewed from the bottom view shown in FIG. 6, forms no part of the claimed design.

(Continued)

As described above in the Description of the Drawings, rear side reflective crown panels are shown by oblique shading in FIGS. 2-5.

1 Claim, 6 Drawing Sheets
